UNITED STATES PATENT OFFICE.

JAMES I. WOOD, OF SALIDA, COLORADO, ASSIGNOR TO WOODS GAS ENGINE COMPANY,
OF SALIDA, COLORADO.

EXPLOSIVE-ENGINE.

970,976.

Specification of Letters Patent. Patented Sept. 20, 1910.

Application filed January 15, 1910. Serial No. 538,239.

To all whom it may concern:

Be it known that I, JAMES I. Wood, a citizen of the United States, residing at Salida, in the county of Chaffee and State 5 of Colorado, have invented certain new and useful Improvements in Explosive-Engines, of which the following is a specification, reference being had to the accompanying drawings.

10 My invention relates to improvements in explosive engines and its objects are to provide an improved means for supplying a sufficient quantity of air to the cylinder, improved means for facilitating the exhaust 15 of the burned gases, an improved means for supplying the oil and igniting the charge.

With the above and other objects in view, the invention consists of the novel construction, combination and arrangement of parts, 20 hereinafter fully described and claimed, and illustrated in the accompanying drawings in which:—

Figures 1 and 2 are side and top views of 25 an explosive engine embodying my improvements; Fig. 3 is a vertical longitudinal section through the cylinder and other parts of the engine; Fig. 4 is a vertical transverse section taken on the plane indicated by the line 4—4 in Fig. 3; Fig. 5 is an end view of 30 the cylinder with one of its heads removed; Fig. 6 is an inner end view of the other head of the cylinder; Fig. 7 is a detail sectional view taken on the plane indicated by the line 7—7 in Fig. 3; Fig. 8 is a detail view of 35 the piston.

Referring more particularly to the drawings 1 denotes the cylinder of my improved engine and 2 and 3 denote the heads of the same. The body 1 of the cylinder is preferably of cylinder shape and surrounded by a water cooling jacket 4 having upper and lower inlet and outlet connections 5, 6. Instead of providing a single port or opening in the intermediate portion of the cylinder 40 1 for the inlet of air I employ a substantially annular series of radially extending openings 7, the outer portions of which communicate with longitudinal passages 8 formed in the wall of the cylinder and extending from the ports 7 to similar radial 45 passages 9 which communicate with the rear end of the cylinder. The ports or passages 9 are formed by grooving the end of the cylinder 1 and they are closed by the head 2,

which latter is bolted or otherwise securely 55 fastened to the cylinder and which contains a suitably packed, centrally arranged, opening 10 for the rod 11 of the piston 12. A radially extending air inlet opening 13 is formed in the bottom portion of the cylinder 60 adjacent its rear end and air is adapted to be drawn by the piston through this opening 13 and to be then forced through the ports or passages 9, 8, 7, into the explosive end 65 of the cylinder in advance of the piston, as presently explained. The exhaust passes out of the cylinder through two openings 14 arranged so that they converge in a single outlet port or opening 15 formed in a boss at the bottom of the cylinder about midway 70 the length of the latter. To deflect the exhaust gases toward the openings 14 and deflect the air coming into the cylinder through the ports 7 the piston may have its end formed with a projecting deflecting 75 rib 16, as shown in the drawing.

On the outer end of the piston rod 11 is arranged a trunnion-carrying head 17, the trunnions of which are pivoted in the arms of a forked pitman rod 18, the fork of the 80 latter straddling a bearing 19 arranged on the bed 20 of the engine for the outer end of the piston rod 11. The other end of the pitman rod 18 is connected to the crank of the shaft 21, which latter is mounted in 85 suitable bearings on the bed and has at its ends the usual fly wheels 22.

The head 3 of the cylinder is bolted or otherwise secured to the latter and consists of a circular plate, from the center of the 90 outer face of which projects a cylindrical enlargement 23 which contains a central bore or passage 24, an outer circular chamber 25, and an inner annular chamber 26. The chamber 26 communicates with the cylinder 1 and in connection with the bore or 95 passage 24 forms a tubular projection 27 against which oil is fed through a radial passage 28 formed in the circular part or plate of the head 3. The outer annular 100 chamber 25 is closed with the exception of its communication with the bore 24 and it is separated from the inner chamber 26 by a radial wall or partition 29, as clearly shown in the drawing. Oil is supplied to 105 the inlet 28 from a force pump 30 arranged on one side of the cylinder and having a discharge pipe or connection 31 communi-

cating with the passage or inlet 28 and an intake pipe or connection 32 leading from a suitable oil tank or other source of supply. The piston of the pump 30 is connected to a slideable rod 33 which is actuated in one direction by a surrounding coil spring 34 and has at its free end a roller 35 to bear against an eccentrically arranged annular member or cam 36 mounted for transverse sliding movement on the engine shaft 21 and held normally in eccentric position by means of a coil spring arranged on one of the guide pins which guide the eccentric 36 in its radial movement. This oil feed pump actuating means forms the subject matter of my co-pending application filed August 17, 1909, Serial Number 513,289, and it automatically varies the supply of oil to the cylinder.

In operation, when the piston makes its return stroke the air in rear of it is forced through the radial passages 9, then through the longitudinal passages 8, and then into the cylinder in advance of the piston through the plurality of radial ports or passages 7, at the same time the exhaust gases passed through the converging outlet ports 14, which latter tend to muffle the exhaust and reduce noise. On the forward stroke of the piston the charge is compressed in advance of the latter and the heat in the boss or member 23 on the head 3 causes the charge to be ignited. In starting the engine the member 23 must be first heated to vaporize the oil which drops upon the tubular projection 27 in the chamber 26, but after the engine has been started these parts will be reheated at each explosion because the explosion will force the flame into the bore 24 and chamber 25 to thoroughly heat the parts of the member 23. It will be further understood that when the engine is in operation the oil dropping upon the heated tube 27 will quickly vaporize and mingle with the charge of air.

While the preferred embodiment of the invention has been shown and described in detail, it will be understood that I do not wish to be limited to the precise construction set forth, since various changes in the form, proportion and arrangement of parts, and in the details of construction, may be re-

sorted to within the spirit and scope of the invention.

Having thus described the invention, what is claimed is:

1. In an explosive engine, the combination of a cylinder formed with a transverse row of inlet ports intermediate its ends, a corresponding series of radial ports at one of its ends, and a series of longitudinal passages connecting the said parts, the cylinder being also formed with an air inlet port arranged adjacent the last mentioned end of the cylinder, and an exhaust port arranged adjacent the first mentioned series of inlet ports, a piston to reciprocate in the cylinder, a head upon one end of the cylinder and provided with an outwardly projecting boss containing a central bore and inner and outer chambers communicating with the bore, the inner chamber also communicating with the cylinder and forming with the bore a tubular portion, said head being also formed with a radial oil inlet passage to discharge oil upon said tubular portion, and a pump actuated by the engine and adapted to force oil through said oil passage.

2. In an explosive engine, the combination of a cylinder, a head at one end thereof and provided with an outwardly extending enlargement containing a longitudinal bore and inner and outer chambers communicating with said bore, the inner chamber also communicating with the cylinder and forming in connection with the bore a tubular portion, means for supplying oil to said tubular portion, and a piston to work in said cylinder.

3. In an explosive engine, the combination of a cylinder, a member containing a longitudinal bore and inner and outer chambers communicating with the bore, the inner chamber also communicating with the cylinder and forming in connection with the bore a tubular portion, and means for supplying oil to said tubular portion.

In testimony whereof I hereunto affix my signature in the presence of two witnesses.

JAMES I. WOOD.
